UNITED STATES PATENT OFFICE.

THOMAS S. HARRIS, OF LOWELL, MASSACHUSETTS, ASSIGNOR TO THE AYER COMPANY, OF LOWELL, MASSACHUSETTS, A CORPORATION OF MASSACHUSETTS.

DESIGN FOR A CARTON.

Application filed October 30, 1925. Serial No. 15,298. Term of patent 14 years.

To all whom it may concern:

Be it known that I, THOMAS S. HARRIS, a citizen of the United States, residing at Lowell, in the county of Middlesex and State of Massachusetts, have invented a new, original, and ornamental Design for Cartons, forming part of this specification.

The design consists in the novel and ornamental carton having as a dominant feature a distinctive Z-band on its surface as illustrated in the accompanying drawing, trated in the drawings.

I claim:

In the drawing:—

Figs. 1 and 2 are perspective views of the substantially as shown, and described. THOMAS S. HARRIS.

Fig. 3 is a fragmentary development of the carton, opened up, and showing the Z-band on the side surfaces thereof.

The design consists in the novel and ornamental carton having as a dominant feature a distinctive Z-band on its surface as illustrated in the drawings.
